Primary Examiner — Darlington Ly(74) Attorney, Agent, or Firm — Leydig, Voit & Mayer Ltd.(57) CLAIM

The ornamental design for a five-sided furniture leg leveler, as shown and described.

DESCRIPTION

1. Five-sided furniture leg leveler

1.1 is a front perspective view of a five-sided furniture leg leveler showing my new design;

1.2 is a front elevation view thereof;

1.3 is a rear elevation view thereof;

1.4 is a top plan view thereof;

1.5 is a bottom plan view thereof;

1.6 is a right side elevation view thereof; and

1.7 is a left side elevation view thereof.

The neutral white fabric shown in the photographs illustrates an environmental backdrop, of which does not form part of the claimed design.

1 Claim, 7 Drawing Sheets(56)
